UNITED STATES PATENT OFFICE.

JAMES B. ANDERSON, OF SHALER TOWNSHIP, ALLEGHENY COUNTY, PENNSYLVANIA.

GAS-BURNER.

1,076,857.

Specification of Letters Patent.

Patented Oct. 28, 1913.

Application filed April 7, 1913. Serial No. 759,334.

To all whom it may concern:

Be it known that I, JAMES B. ANDERSON, a citizen of the United States, and residing in the township of Shaler, in the county of Allegheny and State of Pennsylvania, have invented or discovered new and useful Improvements in Gas-Burners, of which the following is a specification.

My invention consists in a new and improved gas burner for use in connection with boiler and other furnaces.

The objects in view are the reduction of the gas consumption and the increase of the heating effect. I accomplish these objects by the novel construction and arrangement of parts shown.

Generally speaking the burner consists of a gas chamber and a mixing chamber in fixed relation and a cylindrical member slidably mounted between the same, the gas chamber being provided with ports which are engaged by needles mounted on the sliding member. The method shown for introducing the air into the mixing chamber is novel and produces a whirling flame of intense heat. The air chamber is annular and the gas is introduced axially thereof, an annular port admitting the air into the mixing chamber. The valve controlling the admission of air into the air-chamber is adjustably coupled to the sliding member so that any desired ratio between the gas and air may be maintained.

In the accompanying drawings, Figure 1 is a side elevation of my burner; Fig. 2 is a longitudinal section of the same, Fig. 3 is an enlarged end view of the movable needle member; Fig. 4 is an enlarged end view of the gas chamber member, Fig. 5 is an enlarged perspective of the modified form of air-regulating valve used where the air is supplied by a high pressure line; Fig. 6 is a longitudinal sectional view of that form of my burner which utilizes the modified air-regulating valve shown in Fig. 5.

The following is a detailed description of the drawings:

The main elements of the burner are the gas chamber member A; the needle-valve carrying member B, slideable in relation to member A, and the mixing-chamber member C, the valve-carrying member B bridging the space between the gas-chamber member A and the mixing-chamber member C, one end of said needle-valve carrying member B being slideable within a boss 3 carried by said

mixing-chamber C and projecting interiorly thereof.

The gas-chamber member A receives gas as from the supply pipe 1 leading into the outer end thereof, and the inner end of said member, which is preferably tapered to enter the adjacent flaring end of needle-valve carrying member B, is provided with a plurality of gas ports 2. The needle-valve carrying member B is tubular and its inner end is slidably seated in the cylindrical boss 3 of mixer C, a split spring packing ring 4 being seated in a circumferential groove in the needle-valve carrying member B to make a snug fit with the wall of boss 3. The outer periphery of said boss 3 is tapered.

5 is a diametric spider in the bore of needle-valve carrying member B upon which are mounted the needles 6 which engage the ports 2, thus forming a multiple needle valve regulated by the longitudinal movement of needle-valve carrying member B.

The gas-chamber member A and needle-valve carrying member B are supported from member C by means of the parallel rods 7 rigidly secured to said mixing-chamber member C and passing through pierced ears 8 integral with needle-valve carrying member B and similar ears 9 on gas-chamber member A. Needle-valve carrying member B is free to slide on said rods 7 but set screws 10 are provided to lock gas-chamber member A in any desired position. The outward movement of needle-valve carrying member B may be limited by the collar 11 locked by means of set screw 12 in any desired position on rod 7.

13 is an annular air-chamber in mixer member C surrounding the boss 3 and communicating with the mixing chamber 14 by means of the annular port 15 between said boss and the wall of said mixer. As the outer wall of said boss and the wall of said mixing chamber are tapered said port is inwardly inclined, thus intensifying the whirling action of the entering air.

16 is the tapered nozzle.

The air-chamber 13 is provided with a radial inlet port 17 which may be closed or its capacity regulated by a valve 18. The valve 18 may be conveniently mounted on a rock shaft 19 journaled in the walls of port 17. 20 is a cap piece secured to the top of port 17 and provided with a cylindrical throat 21 which may be connected to the discharge of an air-fan.

22 is a lever mounted on the protruding end of rock shaft 19 and securable in any position theron by set screw 23. Said lever is provided with a plurality of holes 24 into any one of which may be introduced the pivot pin 25 journaled in sliding collar 26 mounted on threaded connecting rod 27 and held in any desired position by lock nuts 28. The other end of said rod is hooked and engages a pin 29 on a squared nut 30 riding in guide member 31 and having its position adjusted by screw 32.

33 is a bifurcated bracket extending from mixer C, and 34 is a rock shaft journaled in the arms of said bracket. One end of said shaft is seated in a hole in the base of guide member 31 which may be secured at any desired angle on said shaft by set screw 35.

36 is an arm mounted on said shaft 34 and securable at any angle thereto by set screw 37. 38 is a longitudinal slot in said arms 36. 39 represents a pair of parallel pierced ears integral with needle-valve carrying member B and 40 is a pin extending through said ears and the slot 38 in arms 36.

It is evident that the shutter 18 and needle-valve carrying member B move in unison so that the ratio or proportion between the gas and air supplied to the burner 30 is constant. Said ratio may be varied by means of the numerous adjustments of which the connecting mechanism is capable. Thus the position of the arms 22 may be varied on shaft 19. The pin 25 may engage any of the holes 24 in the arms 22, thus altering the length of the arc of swing of shutter 18. The position of collar 26 on rod 27 may be altered, or the position of nut 30 on screw 32, or guide member 31 or arm 36 on shaft 40 may be altered.

To enable the air valve to be disconnected from the needle valve the hooked end of rod 27 may be thrown off from pin 29. In such case the air supply would be limited to that admitted between gas-chamber member A and needle-valve carrying member B. It is evident that the engagement of the tapered end of gas-chamber member A and the flared end of needle-valve carrying member B is such that the capacity of the annular port thus formed is varied with the altered position of the needle-valve carrying member B in adjusting the needles in the air ports. In other words there is a constant ratio between the gas admitted through ports 2 and the air admitted between gas-chamber member A and needle-valve carrying member B. Thus a proper mixture to sustain combustion is always maintained when the shutter 18 is closed as where it is desired to keep the burner lighted to maintain a minimum heat in the furnace.

In the ordinary operation of the burner, the rod 27 engaging the pin 29, a preliminary mixing of gas and air takes place in

the needle-valve carrying member B, which mixture enters the mixing chamber 14 through the boss 3. The air forced into the air-chamber 13 through the radial port 17 rushes around said annular chamber 13 and escapes through the port 15 in to the mixing chamber 14 in a spiral whirl. The result is a whirling volume of mixed air and gas which forms a whirling flame of great force and intensity at the nozzle. I find this results in a great magnified heat intensity with the use of a much smaller volume of gas than is possible in other forms of burners.

Referring, now, to the form of device shown in Figs. 5 and 6, where the air is supplied to port 17 under high pressure, as from a pump line, I prefer to provide a more accurate valve than shutter 18. Thus I place in port 17 a fixed grating 41 and a co-operating sliding grating 42 pivotally connected by link 43 to an arm 44 on rock shaft 19. I am thus able to obtain a very close adjustment of the amount of air entering the port 17.

What I desire to claim is:—

1. In a gas-burner, a gas-chamber member having ports in the end thereof, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss.

2. In a gas-burner, a gas-chamber member having ports in the end thereof, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss, and said valve-carrying member having a flaring end adjacent said ported end of said gas-chamber member.

3. In a gas-burner, a gas-chamber member having a tapering end provided with ports, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss, and said valve-carrying member having a flaring end adjacent said flaring end of said gas-chamber member.

4. In a gas-burner, a gas-chamber member having ports in the end thereof, a mixing-chamber member spaced therefrom and having a tubular boss projecting interiorly thereof, and a tubular valve-carrying member bridging the space between said gas-

- chamber member and said mixing-chamber member, one end of said valve-carrying member being slidably mounted in said boss, said mixing-chamber member being provided with an annular air-chamber surrounding said boss.
5. In a gas-burner, a gas-chamber member having ports in the end thereof, a mixing-chamber member spaced therefrom and having a tubular boss projecting interiorly thereof, and a tubular valve-carrying member bridging the space between said gas-chamber member, and said mixing-chamber member, one end of said valve-carrying member being slidably mounted in said boss, said mixing-chamber member being provided with an annular air-chamber surrounding said boss, said air-chamber having a radial inlet port, a valve governing the passage of air through said inlet-port, and mechanism for simultaneously reciprocating said valve-carrying member and moving said inlet-port valve.
10. In a gas-burner, a gas-chamber member having ports in the end thereof, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss, said air-chamber having a radial inlet-port.
15. In a gas-burner, a gas-chamber member having ports in the end thereof, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss, said mixing-chamber member being provided with an annular air-chamber surrounding said boss, said air-chamber having a radial inlet-port.
20. In a gas-burner, a gas-chamber member having ports in the end thereof, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss, said mixing-chamber member being provided with an annular air-chamber surrounding said boss, said air-chamber having a radial inlet-port and a restricted outlet.
25. In a gas-burner, a gas-chamber member having ports in the end thereof, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss, said mixing-chamber member being provided with an annular air-chamber surrounding said boss, said air-chamber having a radial inlet-port and a restricted outlet.
30. In a gas-burner, a gas-chamber member having ports in the end thereof, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss, said mixing-chamber member being provided with an annular air-chamber surrounding said boss, said air-chamber having a radial inlet-port and a restricted outlet.
35. In a gas-burner, a gas-chamber member having ports in the end thereof, a mixing-chamber member spaced therefrom and having a tubular boss projecting interiorly thereof, and a tubular valve-carrying member bridging the space between said gas-chamber member and said mixing-chamber member, one end of said valve-carrying member being slidably mounted in said boss, said mixing-chamber member being provided with an annular air-chamber surrounding said boss, said air-chamber having a radial inlet-port and a restricted outlet.
- thereof, a tubular valve-carrying member bridging the space between said gas-chamber member and said mixing-chamber member, one end of said valve-carrying member being slidably mounted in said boss, said mixing-chamber member being provided with an annular air-chamber surrounding said boss, said air-chamber having a radial inlet port, a valve governing the passage of air through said inlet-port, and mechanism for simultaneously reciprocating said valve-carrying member and moving said inlet-port valve.
8. In a gas-burner, a gas-chamber member having ports in the end thereof, a mixing-chamber member having an annular air-chamber communicating with the air-chamber of said mixing-chamber member through an annular port, said annular air-chamber having an inlet-port, a tubular valve-carrying member disposed between said gas-chamber member and said mixing-chamber member and reciprocable to control passage through said gas-chamber ports, superposed stationary and movable gratings in said air-chamber inlet-port, and mechanism for simultaneously reciprocating said valve-carrying member and actuating said movable grating, to maintain a desired ratio between the air and gas.

Signed at Pittsburgh, Penna., this 1st day of April, 1913.

JAMES B. ANDERSON.
